Fig. 3.

Technical drawing illustrating a decorative window frame and valance. The top part shows a horizontal frame with ornate scrollwork at the corners. The frame is labeled with numbers: 15, 16, 20, 22, 26, 21, 27, 18, 19, 21, 23, 24, 25, 26, 27, 28, and W. The bottom part shows a valance with a decorative hem and a ruffled edge, labeled 24 and 25. The drawing is signed "KARL N. STILES Co." and "Mun."

KARL NIXON WATKINS AND STILES O. CLEMENTS, OF LOS ANGELES, CALIFORNIA.

AWNING.

Application filed August 12, 1926. Serial No. 128,854.

Our invention relates to awnings as applied to the windows and doors of buildings for shielding them against sun and rain.

It is a purpose of our invention to provide 5 an awning which functions to shield a window or door against sun rays, and yet being sufficiently open to permit free and unrestricted circulation of air therethrough and thereby providing an awning which can 10 not be injured by winds and which does not shield the window or door opening against the circulation of fresh air.

It is also a purpose of our invention to provide an awning having parts adjustable 15 to cause the awning to function only as a sun shield or as a combined sun and rain shield.

A further purpose of our invention is the provision of an awning which, in its capacity as a sun shield, is adjustable to intercept the 20 sun's rays regardless of the angle of projection of the latter, so as to properly shield the window or door against the sun's rays.

We will describe only one form of awnings 25 embodying our invention and will then point out the novel features thereof in claims.

In the accompanying drawings,

Figure 1 is a view showing in front elevation and partly in section one form of awning embodying our invention in applied position 30 to a window;

Figure 2 is a view showing in plan the frame embodied in the awning shown in Figure 1;

Figure 3 is a central vertical sectional view 35 of the awning shown in Figure 1.

Similar reference characters refer to similar parts in each of the views.

Referring specifically to the drawings, our invention, in this embodiment, comprises a 40 frame made up of a front longitudinal bar 15 to which the outer ends of transverse bars 16 are connected at regular intervals, the inner ends of the bars 16 being connected to the wall of a building through anchoring eyes 17. 45 Chains 18 or similar connectors are secured to the outer ends of the transverse bars 16 as shown in Figure 3, the opposite or upper ends of the chains being connected to the wall of the building by anchor rods 19.

By a frame of this construction, the bars 50 15 and 16 are supported in a horizontal plane, but it is to be understood that by lengthening the chains 18 the frame can be inclined with respect to the horizontal, because of the pivotal connection between the bars 16 and the anchor eyes 17.

The transverse bars 16 are connected at regular spaced intervals by rods 20 which extend longitudinally of the frame and are co-extensive in length therewith, as clearly illustrated in Figure 2. These rods 20 serve to support a plurality of valances 21 which, in the present instance, are strips of canvas or other suitable flexible material. Any one rod 20 supports a valance 21 through the medium of a plurality of rings 22 extended through suitable eyelets in the upper edge of the valance and around the rod, so that the valance is pivotally suspended from the rod to normally occupy a vertical position. The 60 spacing of the rods 20 is such that the valances are suspended in spaced relation to each other to provide intervening openings which extend longitudinally of the frame and are co-extensive in length therewith. The width 65 of the valances is such in respect to the openings that with the frame supported in horizontal position, as shown in Figure 3, and the sun positioned at a point above the awning, the several valances will co-operate in preventing the projection of the sun rays inwardly to the window designated at W in Figure 1. However, the openings allow the 70 passage of sun rays through the awning but only vertically and not at such an angle as to shine into the window. Thus the openings 75 allow transmission of light through the awning so as to properly illuminate the pavement in front of the window. The openings 80 also allow the free circulation of air through the awning, thus rendering it immune to the detrimental action of winds and at the same time allowing the free circulation of air in front of the window and through the window 85 if the latter is open.

The awning also includes a front valance 23 of greater width than the valances 21 and suspended from the bar 15 through rings 22. End valances 24 are suspended from the two endmost bars 16, and these valances merge 90 into side curtains 25, the curtains and side and front valances being provided with fringe, as shown.

Should it be desired to intentionally cause the sun rays to shine into the window, or should it be desired to increase the amount of light transmitted through the awning, as on a cloudy day, the several valances 21 can be simultaneously adjusted from the vertical position shown in solid lines in Figure 3 105 to the rearwardly inclined position shown in dot and dash lines. Such an adjustment is 110

effected through the medium of a plurality of ropes or cords 26 connected to the lower edges of the valances and extended through screw eyes 27 secured in the window frame, 5 and extending downwardly therethrough, as shown in Figure 3, so as to be within easy reach of the operator. By pulling upon the ropes 26, the several valances can be swung rearwardly to the dotted line position and 10 retained in such position by coiling the ropes about wall brackets 28. It is to be understood that when the ropes are released the valances will of themselves gravitate to vertical position.

15 Although we have herein shown and described only three forms of awnings embodying our invention, it is to be understood that various changes and modifications may be made therein without departing from the 20 spirit of the invention and the spirit and scope of the appended claims.

We claim as our invention:

1. An awning comprising a frame adapted to be positioned substantially horizontally 25 when in applied position above a window or door, and a plurality of valances formed of flexible material and suspended from the frame in side by side spaced relation, to thereby normally hang vertically from the frame 30 for lateral movement in response to the action of the wind, and to mutually and constantly define a number of permanent openings for the uninterrupted downward passage of light into the space beneath the awning. 35

2. An awning comprising a frame adapted to be positioned substantially horizontally when in applied position above a window or door, and a plurality of valances formed 40 of flexible material and supported from the frame only along their upper longitudinal edges in side by side spaced relation, to thereby, normally hang vertically from the frame for lateral movement in response to the action of the wind, and to mutually and constantly define a number of permanent openings for the uninterrupted downward passage of light into the space beneath the awning. 45

50 3. An awning comprising a frame adapted to be positioned substantially horizontally when in applied position above a window or door, and a plurality of valances each of which comprises an unsupported strip of fabric, the valances being connected to the frame only along their upper longitudinal edges and disposed in side by side spaced relation to normally hang vertically from the frame for lateral movement in response to the action of the wind, and to mutually and con- 55

stantly define a number of permanent openings for the uninterrupted downward passage of light into the space beneath the awning.

4. An awning comprising a frame including a plurality of valance supporting members arranged in side by side spaced relation and occupying a horizontal position when the frame is in applied position above a window or door, and valances formed of flexible material and suspended from the members so as to normally hang vertically for movement laterally in response to the action of the wind, and to mutually and constantly define a number of permanent openings for the uninterrupted downward passage of light into the space beneath the awning. 65 75

5. An awning comprising a frame adapted to be positioned substantially horizontally when in applied position above a window or door, a plurality of valances formed of flexible material and suspended from the frame in side by side spaced relation so as to normally hang vertically from the frame for waving movement in response to the action of the wind, and front and end valances suspended from the frame in enclosing relation to the first valances and extending below the latter so as to shield the first valances against lateral drafts of air, the said first valances mutually and constantly defining a number of permanent openings for the uninterrupted downward passage of light into the space beneath the awning. 80 85 90

6. An awning structure comprising a frame adapted to be supported above a window or door, and a plurality of valances formed of flexible material suspended from the frame at their upper edges only and disposed in side by side spaced relation so as to normally hang vertically downward and thereby provide between the valances permanent ducts for the free and constant unrestricted passage of overhead light and air, yet shielding the window or door against the direct rays 100 105 of the sun.

7. An awning structure comprising a frame adapted to be supported above a window or door, and a plurality of valances formed of flexible material suspended from the frame at their upper edges only and disposed in side by side spaced relation so as to normally hang vertically downward and thereby provide between the open ended ducts to permit of a constant passage of the elements, air, 110 and overhead light, yet shielding the window or door against the direct rays of the sun. 115
